UNITED STATES PATENT OFFICE.

STANDISH S. BUDLONG, OF ROCKFORD, ILLINOIS.

DESIGN FOR A LAVATORY FIXTURE.

60,396.

Specification for Design.

Patented Feb. 14, 1922.

Application filed July 14, 1921. Serial No. 484,775. Term of patent 14 years.

To all whom it may concern:

Be it known that I, STANDISH S. BUDLONG, a citizen of the United States, residing at Rockford, in the county of Winnebago and State of Illinois, have invented a new, original, and ornamental Design for a Lavatory Fixture, of which the following is a specification, reference being had to the accompanying drawing, forming a part thereof.

In the drawing:—

Figure 1 is a top view of a lavatory fixture embodying my new design; and

Fig. 2, a side elevation of the lavatory fixture.

I claim:

The ornamental design for a lavatory fixture, as shown.

STANDISH S. BUDLONG.
